UNITED STATES PATENT OFFICE.

FRANCIS RAMSEY, OF BROOKLYN, ASSIGNOR OF ONE-HALF TO CORNELIUS H. DELAMATER AND GEORGE H. ROBINSON, BOTH OF NEW YORK, N. Y.

SCREW PUNCHING-PRESS.

SPECIFICATION forming part of Letters Patent No. 247,407, dated September 20, 1881.

Application filed June 13, 1881. (No model.)

To all whom it may concern:

Be it known that I, FRANCIS RAMSEY, of the city of Brooklyn, in the county of Kings and State of New York, have invented a certain 5 new and useful Improvement in Screw Punching-Presses, of which the following is a specification.

My invention is applicable to all punches or 10 punching-presses in which the punch is forced forward by a screw to which it is attached, and does not rotate with the screw. Its object is to reduce the friction of the screw upon the punch and so enable the screw to turn freely 15 without turning the punch, and thereby rendering the latter liable to be broken.

To this end the invention consists in the combination, in a punch, of a frame and die, a screw, a punch fitting loosely in a socket in the screw, both the bottom of the socket and 20 the inner end of the screw being concave, a thrust-block having convex surfaces fitting the bottom of the socket and the inner end of the punch, and a collar or cap-plate secured upon the end of the screw and fitting against a 25 shoulder on the punch, to retain the latter in place, as particularly hereinafter described.

In the accompanying drawings, Figure 1 represents a side view, partly in section, of a screw-punch embodying my invention, in which 30 the thrust block or piece consists of a sphere; Fig. 2 represents a thrust block or piece consisting of a hemisphere, which is supported on a second hemisphere; and Fig. 3 represents a similar view to Fig. 2, but showing the hemispherical thrust block or piece supported by 35 a number of flat disks, which are, in turn, supported on a second hemisphere.

Similar letters of reference designate corresponding parts in all the figures.

Referring first to Fig. 1, A designates a casting, constituting the frame of the punch, and constructed with an opening or throat, A', adapted to receive the edge of a boiler-plate to be punched.

45 B designates the die, and C designates the punch, which is loosely fitted in a socket, a, in the end of the screw D, wherein it is held by a collar or annular cap, b, bearing against a shoulder, c, on the punch, and secured to the 50 end of the screw D by screws d or otherwise. The screw D fits in a nut in the frame A, and has holes e in its head, in which a bar may be inserted to turn it. The punch C shown is what

is known as a "spiral shearing-punch," but any kind of punch might be substituted. The 55 inner end of the punch C is concave, as clearly shown, as also is the bottom of the socket a in the screw D, thus forming between the two parts a spherical cavity, and between the end of the punch and the bottom of the socket in 60 said cavity is placed a sphere, E, which serves as a thrust block or piece to receive the thrust of the screw upon the punch. The sphere may either turn with the screw or remain stationary 65 with the punch, but in either case it greatly lessens the friction between the turning screw and the non-rotary punch. The concave inner end of the punch C forms a cavity or cup to retain oil when the punch is used in an upright position, as shown, and when inverted 70 the oil is retained by the socket a.

In lieu of the thrust block or piece being spherical, it may be made in the form of a hemisphere, as shown at F, Fig. 2, and it may rest upon a second hemisphere, F', as in Fig. 75 2, or upon a flat disk, f, of which one or a number may be placed between the two hemispheres, F F', as shown in Fig. 3.

In all the examples of my invention here shown the inner end of the punch is concave, 80 and the thrust block or piece is correspondingly convex, and while the spherical thrust block or piece shown in Fig. 1 may perhaps work with the least friction and be the most desirable, they all enable the oil to be retained 85 in the concave inner end of the punch when used in an upright position, as here shown.

The devices shown in Figs. 2 and 3 may each be considered as one thrust-block composed of 90 two or several pieces.

What I claim as my invention, and desire to secure by Letters Patent, is—

The combination of the frame A, the die B, the punch C, having a concave inner end, and the shoulder c, the screw D, provided with a 95 socket, a, having a concave bottom, the thrust-block having convex surfaces fitting the inner end of said punch and the bottom of the socket, and the collar or cap-plate b, secured to the end of the screw, and bearing against 100 the shoulder c of the punch, substantially as specified.

FRANCIS RAMSEY.
